UNITED STATES PATENT OFFICE.

JOHN ERICKSON, OF CHICAGO, ILLINOIS, ASSIGNEE, BY MESNE ASSIGNMENTS, TO
AUTOMATIC ELECTRIC INC., OF CHICAGO, ILLINOIS, A CORPORATION OF DELA-
WARE.

ELECTROMAGNETIC RELAY.

Application filed December 31, 1919. Serial No. 348,548.

My invention relates in general to electromagnetic relays and has for its object the provision of a relay having a variable time constant; and more especially, a relay having a variable time constant which is adjustable between much wider limits than are the well known types of slow acting relays now in common use. The preferred means used to attain this and other useful objects will be described fully hereinafter, reference being had to the accompanying drawing.

In the drawings, Fig. 1 shows a relay of my improved type connected for use in operating a meter a predetermined time after its circuit is closed; Figure 2 shows another modification of the relay which is used in combination with a differential relay to hold a circuit open for a certain definite time interval.

Referring first to Fig. 1 the operation of the relay may be briefly described as follows: When the circuit of the relay 2 is closed by the contact device 3, the relay is energized and closes its contact springs 4 and 5. The outside contact spring 4 has a rod 6 which is attached to it by any suitable means, as for example, by soldering, which carries an adjustable weight 7. When the contact springs are closed the weight 7 begins to vibrate rapidly, and rapidly interrupts the circuit of the meter M which was closed when the contact springs 4 and 5 first came into engagement with each other. The magnet of the meter is of high impedance and consequently does not fully energize so as to attract its armature until the weight 7 has stopped vibrating. I have found by experiment that with this arrangement I can delay the operation of the meter as much as five seconds, and the period of delay is readily adjustable by regulating the stroke of the relay armature and also to some extent by moving the weight 7 up and down on the rod 6.

One of the applications in which I have used this form of my invention is in connection with a master switch of the general type shown in the U. S. Patent to Keith No. 1,185,510, granted May 30, 1916. In a master switch of this type when all the outgoing trunk lines are busy, the master switch is in continuous operation. It is desirable in order to keep a close check on traffic conditions to use a meter in connection with each master switch in order to register the num-

ber of times the several groups of trunk lines become busy. In using my improved relay the contact device 3 may be mounted upon the starting relay of the master switch which relay is necessarily energized whenever the master switch is operating. The operation of the starting relay when the master switch moves the line switch plungers from one trunk to the next in its ordinary operation of preselecting idle trunks does not close the circuit of relay 2 long enough to permit the meter to register; and the longer closure of the circuit of relay 2 caused by the locking up of the master switch starting relay while the master switch operating spring is being retensioned by the solenoid is still not long enough to cause the meter to register. However, when all the trunks are busy the master switch will operate continuously and the starting relay will remain energized while it is operating, thereby ensuring that the meter M will finally be operated to register.

In Fig. 2 I have shown a modification of the invention which will be easily understood. The purpose of the embodiment of the invention shown in this figure is to produce a prolonged opening of the circuit extending over conductor 20 whenever the relay 10 is energized. The operation is as follows: When the circuit of relay 10 is closed at contact devices 21 it attracts its armature and closes contact springs 12 and 13. By this operation a circuit is completed through the two windings of the differential relay 11 in parallel. The circuit for one of the windings, however, includes the contact springs 14 and 15 and is rapidly interrupted by vibrations of the weight 17. When relay 10 is first energized, therefore, the differential relay 11 is unbalanced and is operated to attract its armature and separate contact springs 18 and 19. As soon as the weight 17 has ceased vibrating contact springs 14 and 15 remain closed and the circuit through both its windings being now closed continuously, differential relay 11 will retract its armature and again close contact springs 18 and 19. Regulation of the time interval of the differential relay is accomplished by adjusting the weight 17 on rod 16, and by regulating the length of stroke of the armature of relay 10.

In adjusting the relays in both of the forms shown herein, Figs. 1 and 2, wide adjustments of the time constant are accom-

plished by regulating the stroke of the relay armatures. The adjustment of the weights by moving them up and down changes the frequencies of the vibrations and while it alters to some extent the duration of a series of vibrations it is of use chiefly in adjusting the frequency to the natural period of the device which has to be operated. For example, in Fig. 1 the vibrations of the weight 7 must be so fast that the short impulses of current sent through the meter are insufficient to fully energize its operating magnet. In case a meter or relay having lower impedance or a lighter armature which would respond more quickly is substituted for the meter M the weight 7 would have to be moved up higher on the rod 6 to produce vibrations of higher frequency in order to prevent the operation of such meter or relay.

Having described my invention what I desire to have secured and protected by Letters Patent will be pointed out in the appended claims.

What I claim as my invention is:

25. 1. A relay having contact springs, means for closing said springs when the relay is energized, and a weight attached to one of said springs to cause the same to vibrate and delay the permanent closure of said springs while said relay is energized.
2. A relay having circuit controlling contact springs, a weight attached to one of said springs to cause the same to vibrate and delay the permanent closure of said springs while said relay is energized.
3. A relay having contact springs for closing a circuit, and means for causing one of said springs to rapidly vibrate and interrupt the contact while the relay remains energized.
4. A relay having contact members for closing a circuit when the relay is energized, a weight attached to one of said contact members to cause the same to vibrate when the relay is energized, said member vibrating with constantly diminishing amplitude,

and means for adjusting the said weight to regulate the time consumed in diminishing the amplitude of vibration.

5. A relay having circuit controlling springs, said relay when energized causing its armature to be permanently attracted, and additional means on said relay for opening said circuit controlling springs and for preventing the permanent closure of said circuit controlling springs for a predetermined interval after the armature is attracted.

6. A relay having circuit controlling springs, said relay when energized causing its armature to be permanently attracted, and a weighted arm on said relay for preventing the permanent closure of said circuit controlling springs for a definite interval after the armature is attracted.

7. A relay having circuit controlling springs, said relay when energized causing its armature to be permanently attracted, an arm attached to one of said springs, and means on said arm for delaying the permanent closure of said circuit controlling springs for a predetermined interval after the armature is attracted.

8. A relay having a pair of normally open contact springs, an armature for said relay effective when the same is energized to close said springs, and means on one of said springs for delaying the permanent closure of said springs for a predetermined period after the continued energization of said relay.

9. In combination with a relay having a pair of contact springs and an armature for operating them, of a member attached to said springs set in motion by the actuation of said armature and effective to delay the permanent operation of said springs until after said armature has been in an operated position for a definite period.

Signed by me at Chicago, Cook County, Illinois, this 24th day of December, 1919.

JOHN ERICKSON.
